Des. 237,488
Patented Nov. 4, 1975

237,488

ROTATABLE BLOCK GAME

Albert Stubbmann, 746 Dakota Trail,
Franklin Lakes, N.J. 07417

Filed Feb. 22, 1973, Ser. No. 334,543

Term of patent 14 years

Int. Cl. D19—07

U.S. Cl. D19—64

FIG. 1.

FIG. 2.

FIG. 3.

FIG. 4.

FIG. 1 is a perspective view of a rotatable block game showing my new design;

FIG. 2 is a front elevational view thereof;

FIG. 3 is a side elevational view thereof; and

FIG. 4 is a top plan view thereof.

The undisclosed sides of the individual blocks are of the same configuration as that of the sides shown.

I claim:

The ornamental design for a rotatable block game, as shown and described.
